UNITED STATES PATENT OFFICE.

EMIL GATHMANN, OF BALTIMORE, MARYLAND.

PROJECTILE-FUSE TIME-TRAIN RING.

1,301,928.

Specification of Letters Patent. Patented Apr. 29, 1919.

Application filed August 30, 1917. Serial No. 188,934.

To all whom it may concern:

Be it known that I, EMIL GATHMANN, a citizen of the United States, residing at Baltimore, State of Maryland, have invented a new and useful Improvement in Projectile-Fuse Time-Train Rings, of which the following is a specification.

This invention relates to an improvement in projectile-fuse time-train rings.

10 In the time-train rings for dial type fuses, mostly used heretofore, it has been customary to provide powder grooves having parallel walls, the grooves being open to the rear of the ring or toward the body of the projectile. The parallel side walls of the grooves are also parallel with the longitudinal axis of the projectile fuse in the old construction. Tests have recently been made with converging side walls of the 20 grooves, and I am aware that a patent has been granted for this converging construction of side walls.

The powder composition of the fuse time ring is inserted in the groove under very 25 heavy pressure per square inch of surface of groove, and it is desirable that the density and hardness of the powder train be as nearly homogeneous throughout all the portions of groove as possible. The type of 30 groove heretofore used has had a ratio of depth approximately 1.5 to width=1.00 or in other words the groove was approximately one and one-half times as deep as wide. In the present artillery practice of 35 high velocity projectiles great accuracy is essential in the uniformity of burning of time train. The necessity of greater uniformity in the hardness and density of the powder composition pressed in the powder 40 groove is thus evident, as it is well known to those skilled in the art that density and hardness are most important factors in the ignition, inflammation and combustion of all powder products. I have found by 45 experiment that the density and hardness can be made more homogeneous, and correspondingly the rate of burning more uniform if the groove is constructed so that the depth of same is approximately equal 50 to the width, or even less than the latter.

As before stated, the powder composition is forced in the time train groove under heavy pressure. In the usual type of groove with parallel side walls it is however held 55 within the groove only by adhesion of the train composition with the train ring ma-

terial, as the parallel side walls of groove are also parallel with the major axis of projectile and fuse. The side walls defining the groove have thus, as used heretofore, always 60 been constructed deeper than their width, so as to present considerable surface to adhesion and friction which was their sole means of support within the groove. In my construction I prefer to employ parallel side 65 walls of the train ring groove, but slope these parallel walls at an angle from that of the major axis of the projectile and the fuse, by which construction I obtain the equivalent of an undercut retaining wall 70 without the narrowing of width of the groove and its disadvantageous construction on loading and pressing of the powder composition in the groove.

With these and other objects not specifically mentioned in view, the invention consists in certain parts and constructions which will be hereafter fully described and then specifically set forth in the claims hereunto appended.

In the accompanying drawings, which 75 form a part of this specification, and in which like characters of reference indicate the same or like parts, Figure 1 is an inverted plan view of a projectile-fuse time-train ring constructed in accordance with the invention; Fig. 2 is a cross-sectional view taken on line 2-2 of Fig. 1; and Fig. 2^a is an enlarged fragmentary cross sectional view of a preferred form of groove. 80 In carrying the invention into effect there is provided a projectile-fuse time-train ring 85 provided with a groove of approximately uniform depth (D) and width (W) with approximately parallel side walls and preferably rounded at the bottom, and with means other than adhesion and undercut side walls for resisting displacement and disintegration of the powder composition 90 during gun fire and projectile acceleration 100 as well as during the various machining and manufacturing operations in assembly of the fuse.

In the preferred construction as shown in the accompanying drawings, the ring is provided with a powder composition groove and approximately parallel side walls inclining rearwardly and inwardly with reference to the major axis A—A of projectile and fuse. The device selected to illustrate the invention is but one of many possible concrete embodiments of the same, and the invention is 105 110

not restricted to the precise details of the structure as shown and described.

Referring to the drawings, 3 indicates a projectile fuse-time-train ring generally of a well known character, but provided with a powder composition groove 4, having a rounded bottom 8, an inner retaining wall 6, and an outer retaining wall 5, said walls being approximately parallel one with the other, but none of their elements are parallel with longitudinal axis A—A of the projectile and fuse, as clearly shown in Figs. 2 and 2^a. As before stated, it is most desirable that the powder composition be homogeneous and of uniform density and hardness and in the ring groove heretofore ordinarily of greater depth than width, this is difficult of attainment even under very high loading pressures, also, as the deeper the groove, the more difficult to obtain uniform density and hardness. Adhesion only, tends to keep the powder composition in the groove, and the ring being deep, relative to its width, it is difficult to obtain a train of powder of a homogeneous uniform density and hardness, which density and hardness are most important factors in the time of burning of the fuse, as is well known to those familiar with the art. In the present device the width W and depth D, as shown on Figs. 2 and 2^a, are approximately of the same dimension, and the actual surface which governs the size of loading die is enlarged as shown at S; thus allowing of a free unimpeded flow of powder composition during the pressing operation, and consequently thus obtaining a greater uniformity in hardness and density of the powder composition train. These last named results are not readily obtainable in the lately advocated undercut groove construction which is described in a recent U. S. patent. As the loading pressure on the powder composition when pressed within the groove is far greater than any possible pressure due to inertia of composition or set back due to firing of projectile from gun, and as the walls rigidly support the same against bodily movement, it will be readily understood that disintegration or breaking up of the train of powder composition cannot occur. It should be noted that the free face of the powder composition, when the fuse is

assembled, is pressed against a washer of felt or the like material fitted to a platform either on the body of the fuse or on a time train ring, mounted behind the one here shown. Other forms of grooves not shown but capable of effecting the same results may of course be used in place of the preferred form shown in the drawings.

What is claimed is:

1. A projectile-fuse time-train ring provided with a powder composition groove open to the rear end and having approximately parallel retaining side walls, none of the elements of the said side walls being parallel with the longitudinal axis of the fuse.

2. A projectile-fuse time-train ring provided with a powder composition groove open to the rear end and having approximately parallel retaining side walls, and a rounded bottom, none of the elements of the said side walls being parallel with the longitudinal axis of the projectile-fuse.

3. A projectile-fuse time-train ring provided with a powder composition groove open to the rear end and having side walls which are portions of co-axial cones having those adjacent elements that lie in the same axial plane approximately parallel to each other.

4. A projectile-fuse time-train ring provided with a powder composition groove open to the rear end and having approximately parallel side walls, none of the elements of the side walls being parallel with the longitudinal axis of the fuse, the open width of the aforesaid composition groove being equal approximately to its depths.

5. A projectile-fuse time-train ring provided with a powder composition groove open to the rear having side walls approximately parallel to each other, the said side walls being portions of approximately co-axial cones.

6. A projectile-fuse time-train ring provided with a powder composition groove having side walls approximately parallel to each other, the said side walls being portions of approximately co-axial cones.

In testimony whereof I have signed my name to this specification.

EMIL GATHMANN.
